UNITED STATES PATENT OFFICE.

JEAN A. H. BARKEIJ, OF LOS ANGELES, CALIFORNIA.

INTERNAL-COMBUSTION ENGINE.

Application filed December 5, 1923. Serial No. 678,624.

To all whom it may concern:

Be it known that I, JEAN A. H. BARKEIJ, a subject of Holland, residing at Los Angeles, in the county of Los Angeles and State 5 of California, have invented a new and useful Internal-Combustion Engine, of which a specification is set forth below.

In this specification, and the accompanying drawing, I shall describe and show a 10 preferred form of my invention, and specifically mention certain of its more important objects. I do not limit myself to the forms disclosed, since various changes and adaptations may be made therein without departing 15 from the essence of my invention as hereinafter claimed; and objects and advantages, other than those specifically mentioned, are included within its scope.

My invention relates to internal combustion engines of the two cycle type. Among 20 its principal objects are; first, to do away with the necessity for crank case compression, hitherto used practically universally in engines of this type, and thus avoid accumulation of crank case lubricants in the 25 combustion chambers; second, to afford facilities for scavenging by the use of compressed air prior to the introduction of the explosive mixture, thus securing better fuel 30 economy and cleaner operation; third, to balance in a large measure the inertia forces exerted by the reciprocating masses, so as to effectively reduce vibration and permit 35 higher operating speeds; and fourth, to accomplish the above objects in a relatively simple construction adapted for delivering a large amount of power in proportion to its 40 dimensions and weight.

My objects are attained in the manner 45 illustrated in the accompanying drawing, in which—

Figure 1 is a central longitudinal section, in elevation, of a two-cylinder engine of my improved construction; and

Figures 2, 3 and 4 are reduced scale cross sections, in plan, taken on the lines 2—2, 45 3—3 and 4—4 of Fig. 1 respectively.

Similar reference numerals refer to similar parts throughout the several views.

My engine comprises either a single pair, 50 or a plurality of pairs, of power cylinders with opposed power pistons therein, and compression pistons in co-operative relation thereto. The simplest form, involving the 55 use of a single pair of power cylinders, has been selected for illustrative purposes.

Referring to the drawing it will be noted that each of the power cylinders 5 is provided with a water jacket 6 extending throughout the whole of its power producing length, wherein the combustible gases are burned. It will also be seen that each of these cylinders is provided with a relatively large diameter, but axially short counterbore 7, at its top. The upper ends of the 60 cylinders are closed by peculiarly shaped, double-capped, heads 8. One of these is shown broken in Fig. 1, at 9, to better illustrate certain features that would otherwise be concealed in this view.

Within the counterbore of each cylinder there is a large compression piston 10 adapted to reciprocate therein. These pistons have tubular trunks 11 adapted to work within bore 5 of the power cylinders, and projecting therefrom at their lower ends. The trunks are connected in each case to crank 70 shaft 12 of the engine by a pair of connecting rods 13, attached in any suitable manner as by the internal collars 14, and diametrially opposed wrist pins 15.

Trunks 11 are interiorly divided by intermediate transverse partitions 16, serving as reaction heads for the power pistons 17 and, at the same time, as secondary piston means 85 whereby a portion of the power of the exploded gases is delivered to the crank shaft through connecting rods 13. For convenience of inspection and cleaning, I prefer to provide the transverse partitions with removable plates 18, whereby access is had to the space below them. Power pistons 17 are connected to the crank shaft of the engine 90 by connecting rods 19 in the usual manner.

Each tubular trunk 11 has a pair of longitudinally aligned ports 20, adapted to register with the respective ends of a passage 21 in the cylinder casting. This permits of establishing communication between the spaces on the two sides of partitions 16 100 when the various parts are in the operating positions shown in the left half of Fig. 1. At this time also a port 22, in the opposite wall of the trunk, is in registry with the outlet of passage 23, leading from the space 105 below large piston 10 of the other cylinder of the engine.

It is to be noted that the central cup-shaped portions of cylinder heads 8 do not closely fit the bores of trunks 11. There is 110 in fact a considerable annular space 24 separating these parts, so that gas compressed

between pistons 10 and their respective cylinder heads can flow downward through this annular space into space 25 and, from there, into space 26 through ports 20 and 5 passage 21.

Inlet ports 27 in the walls of counterbores 7 allow of introducing an explosive mixture or combustible gas into the spaces above pistons 10 for compression therein. The 10 upper edges of these pistons serve to close and open these ports at the proper moment in the operating cycle. Similar inlet ports 28, in the opposite walls of the counterbores and lower down therein, permit of the entry of air for compression beneath pistons 10, for use in scavenging. The lower edges of the compression pistons serve to open and close ports 28 at the proper operating times. Fig. 2 shows how ports 27 and 28 may conveniently be arranged for bolting on manifold connections, by means of studs 29.

At the lower part of trunks 11 there is an exhaust port 30, adapted to register with a similar port 31 in the walls of the cylinder. These ports are opened and closed at the proper times in the operating cycle by the action of the upper edge of power pistons 17. Spark plugs 32, in the upper portion of the power cylinders, communicate with spaces 26 through the lowermost of ports 20 for firing the charge at the proper time in the operating cycle.

In Fig. 1 all of the cranks are shown on dead centers. The explosive mixture in space 26 of the right hand cylinder has been compressed between partition 16 and piston 17, and is ready to be fired by spark plug 32 through port 20. After firing, piston 17 will descend and partition 16, with trunk 11 and piston 10, will ascend. In each case power will be delivered to crank shaft 12 through the respective connecting rods. Also a charge of fresh explosive mixture, previously drawn into the space above piston 10, will be compressed therein; and a charge of air will be drawn into the space below piston 10 to be compressed upon its next downward journey.

When the crank has revolved 180 degrees, 56 and the cranks are respectively on their opposite dead centers, the various parts will have assumed positions corresponding to those shown in the left hand half of Fig. 1. Just previous to this time exhaust ports 30 and 31 have come into registry, and been uncovered by the downward movement of piston 17. The burned and expanded power gas has been discharged through these ports under the action, first, of its own terminal pressure, and, second, by reason of the compressed scavenging air coming into space 26 through port 22 from the under side of the large compression piston in the other side of the engine. Fresh explosive mixture, compressed in the space above piston

10 and in space 25 in this left side of the engine, has been admitted to space 26 following the scavenging air, and fills the latter space. A slight rotation of the crank shaft will next close all of the opened ports 70 and cause respectively an upward and downward motion of piston 17 and partition 16. Further rotation of the crank shaft will result in continuous progressive compression of the fresh explosive mixture trapped between the piston and partition until the various operating parts have again arrived in the positions shown in the right half of Fig. 1, corresponding to the completion of the operating cycle. 75

It is to be noted that the lower edge of port 22 is below the corresponding edge of lowermost port 20, so as to be opened slightly in advance of the latter. This allows the compressed scavenging air to enter 80 space 26 and do its work before the introduction of the compressed fresh explosive mixture. It is also to be noted that, by slight changes in proportions of parts and location of ports the use of the spaces above and 85 below pistons 10 may be reversed. That is to say the incoming explosive mixture may be initially compressed below pistons 10, instead of above them, provided a corresponding change is made in the manner of compressing the scavenging air. 90

It will be obvious that my construction and arrangement of parts permits of very efficient water-jacketing throughout the full combustion length of the power cylinders. 100 Also that the effects of inertia in the reciprocating parts are largely balanced against each other. The larger and heavier assemblies attached to trunks 11 have a shorter travel than the lighter assemblies 105 attached to pistons 17 in substantially inverse proportion to the weights. Vibration tendencies are thus largely eliminated, and the permissible speed of the engine is relatively high. This, in turn, results in 110 greater power per unit of weight, and reduces the cost per unit of output.

In an application for Letters Patent for an internal combustion engine filed April 9th, 1923, Serial Number 631,022, I disclosed a construction somewhat similar to that herein described. There are very material differences in the two constructions, however, and the claims herein do not conflict, with the claims of said application. 115

I claim as my invention herein described:

1. An internal combustion engine comprising counterbored cylinders; compression pistons within said counterbores having tubular trunks within said cylinders; and power pistons within said trunks adapted for reciprocating oppositely thereto; said trunks and said power pistons being operatively connected to a common crank shaft. 125
2. An internal combustion engine com- 130

- prising counterbored cylinders; compression pistons within said counterbores having transversely partitioned tubular trunks within said cylinders; and power pistons within said trunks adapted for reciprocating oppositely thereto; said trunks and said power pistons being operatively connected to a common crank shaft.
3. An internal combustion engine comprising counterbored cylinders; compression pistons within said counterbores having tubular trunks, with removable transverse partitions therein, within said cylinders; and power pistons within said trunks adapted for reciprocating oppositely thereto.
4. An internal combustion engine comprising counterbored cylinders; compression pistons within said counterbores having tubular trunks within said cylinders; and power pistons within said trunks; said power pistons and trunks of each cylinder being operatively connected to a common crank shaft for opposite reciprocation.
5. An internal combustion engine comprising counterbored cylinders; compression pistons within said counterbores having transversely partitioned tubular trunks within said cylinders; and power pistons within said trunks; said power pistons and trunks of each cylinder being operatively connected to a common crank shaft for opposite reciprocation and delivering power thereto.
6. An internal combustion engine comprising counterbored cylinders; compression pistons within said counterbores having transversely partitioned tubular trunks within said cylinders; and power pistons within said trunks; said power pistons and trunks of each cylinder being operatively connected to a common crank shaft for opposite reciprocation with throws in approximately inverse proportion to the square roots of the respective masses of the reciprocating parts.
7. An internal combustion engine comprising; an adjacent pair of counterbored cylinders; compression pistons within the counterbores, having tubular trunks within the respective cylinders; power pistons within the trunks; and means for intermittently connecting one side of each compression piston to the inner end of its trunk, and the other side to the inner end of the adjacent trunk; said trunks and the respective power pistons being adapted for reciprocating oppositely.
8. An internal combustion engine comprising; an adjacent pair of counterbored cylinders; compression pistons within the counterbores, having tubular trunks within the respective cylinders; power pistons within the trunks; and means for intermittently connecting one side of each compression piston to the inner end of its
- trunk and the other side to the inner end of the adjacent trunk; said trunks and the respective power pistons being operatively connected to a common crank shaft for reciprocating oppositely.
9. An internal combustion engine comprising; an adjacent pair of counterbored cylinders; compression pistons within the counterbores, having tubular trunks within the respective cylinders; power pistons within the trunks; and means for intermittently connecting one side of each compression piston to the inner end of its trunk, and the other side to the inner end of the adjacent trunk; said trunks and the respective power pistons being operatively connected to a common crank shaft for reciprocating oppositely; and said means being operative by the movement of the pistons.
10. An internal combustion engine comprising; an adjacent pair of counterbored cylinders; compression pistons within the counterbores, having tubular trunks within the respective cylinders; power pistons within the trunks; and means for intermittently connecting one side of each compression piston to the inner end of its trunk, and the other side to the inner end of the adjacent trunk; said trunks and the respective power pistons being operatively connected to a common crank shaft for reciprocating oppositely; and said means consisting of passages having ports uncoverable by the movement of the pistons.
11. An internal combustion engine comprising counterbored cylinders; compression pistons within said counterbores having tubular trunks within said cylinders; power pistons within said trunks adapted for reciprocating oppositely thereto; a passage connecting each cylinder with one end of its counterbore; a passage similarly connecting with the opposite end of the other counterbore; an exhaust port in each cylinder; and ports in said trunks adapted to register with said cylinder passages and ports.
12. An internal combustion engine comprising counterbored cylinders; compression pistons within said counterbores having tubular trunks within said cylinders; power pistons within said trunks adapted for reciprocating oppositely thereto; a passage connecting each cylinder with one end of its counterbore; a passage similarly connecting with the opposite end of the other counterbore; an exhaust port in each cylinder; ports in said trunks adapted to register with said cylinder passages and ports; and means operatively connecting the crank shaft of said engine with said power pistons and trunks.
13. An internal combustion engine comprising counterbored cylinders; compression pistons within said counterbores hav-

ing tubular trunks within said cylinders; power pistons within said trunks adapted for reciprocating oppositely thereto; a passage connecting each cylinder with one end 5 of its counterbore; a passage similarly connecting with the opposite end of the other counterbore; an exhaust port in each cylinder; ports in said trunks adapted to regis-

ter with said cylinder passages and ports; air and gas inlet ports in said counterbores 10 adapted to be closed and opened by the movement of said compression pistons; and means operatively connecting the crank shaft of said engine with said power pistons and trunks.

JEAN A. H. BARKEIJ.
